[57] CLAIM

The ornamental design for a magneto-optical business card; as shown and described.

DESCRIPTION

FIG. 1 is a front perspective view of the magneto-optical business card of the present invention;

FIG. 2 is a front elevational view of the magneto-optical business card of FIG. 1;

FIG. 3 is a rear elevational view of the magneto-optical business card of FIG. 1;

FIG. 4 is a bottom or top plan view of the magneto-optical business card of FIG. 1; and,

FIG. 5 is a right side elevational view or a left side elevational view of the magneto-optical business card of FIG. 1.

The broken lines of surface indicia are not part of the claimed design.
